UNITED STATES PATENT OFFICE.

FREDERICK HOWARD LIVENS, OF LINCOLN, AND WILLIAM HOWARD LIVENS, OF LONDON, ENGLAND.

GAS-PROJECTILE.

1,335,343.

Specification of Letters Patent. Patented Mar. 30, 1920.

Application filed July 2, 1919. Serial No. 308,237.

To all whom it may concern:

Be it known that we, FREDERICK HOWARD LIVENS, a subject of the King of Great Britain, residing at Sheaf Iron Works, Water-side South, Lincoln, England, and WILLIAM HOWARD LIVENS, a subject of the King of Great Britain, residing at 32 Howitt road, Hampstead, London, England, have invented new and useful Improvements Relating to Gas-Projectiles, of which the following is a specification.

This invention relates to bombs, shells and like projectiles of the unrifled class, more particularly used for emitting lethal vapors, and has for its object the facilitating of the manufacture of the same by avoiding welding and at the same time providing a more efficient construction.

According to the present invention the projectile is constructed from a single circular metallic plate by first cupping and passing through dies to form a thimble of which the closed end has the least thickness of metal and the open end the greatest thickness, and in subsequent operations indenting the closed end and closing in its open end. The thickness of the walls obtained thus varies in accordance with the stresses which have to be borne resulting in a greater content for a given weight of projectile, while the integral construction permits the bursting charge to be displaced at will without presenting a passage for the escape of the contents of the projectile.

The accompanying drawing shows, by way of example, in axial section a bomb for emitting lethal vapors constructed according to the invention.

The finished bomb consists of a cylinder having one closed end, the other end being left with a small hole. The closed end or nose is indented to form a container *a* which is tapped and fitted with an adapter *e*. The container *a* receives a bursting charge contained within a gain *f*. The small open end *c* of the base of the bomb is tapped and fitted with a plug *d*.

The bomb is made from a circular plate which is cupped and pressed through a die and drawn into a thimble, the head of the thimble being a semi-ellipsoid, all of which can be done in one operation. This thimble will be as shown in the drawing but there will be no indentation, and the base *b* is not closed in. As will be observed the closed end

of the thimble has the least thickness of metal, then the cylindrical walls, while the open end *b* has the greatest thickness of metal. The closed end of the thimble is then taken to other dies, and the nose pushed inward and drawn at the same time to form the container *a*. The open end is now drawn together under swages or by dies into the semi-spherical shape illustrated to form the base of the projectile, which base can be twice the thickness of the cylindrical part, and so resist more efficiently the shock of the propellant.

As shown, the base end of the projectile is of substantially uniform thickness and merges into the cylindrical wall also of uniform but lesser thickness, while the nose end is the thinnest portion, the wall forming the chamber for the bursting charge being more or less progressively thinner toward the inner end.

The wall of the cylindrical part can, however, be made thicker next the base than next the nose end or the whole projectile may be progressively thinner from the base to the nose.

The only machining which may be required is the turning of the base end to a more regular form.

By this construction no welding is necessary and a source of weakness and difficulty in bombs or shells to be charged with gas is consequently avoided.

Such proportionate thickness can be obtained in the walls that the projectile will stand a high propelling charge without setting up, and at the same time a capacity such that measured by the weight of water held, this weight will be equal approximately to half the weight of the empty bomb.

The efficiency of a gas projectile=

$$\frac{\text{carrying capacity}}{\text{gross weight}}$$

100

To increase the efficiency of the gas projectile either the carrying capacity, that is, the quantity of gas which it holds, may be increased or the gross weight of the projectile decreased. By constructing the projectile so that its wall is progressively thinner from the base to the nose and by elimination of joints between the container for the bursting charge and that for the gas, and by the further elimination of joints at each 110

end of the gas container characterizing prior types of gas shells, the carrying capacity is increased while the gross weight is also decreased, thus effecting increased efficiency of the gas projectile.

What we claim is:

1. A drawn, gas projectile having a structure which gives maximum efficiency per quantity of metal therein, said structure comprising a thick base with the wall progressively thinning to the nose portion.
- 10 2. A drawn, gas projectile having separate compartments for holding lethal vapor and bursting charge, the walls of said compartments being integral with each other.
- 15 3. A drawn, gas projectile having a structure which gives maximum efficiency per quantity of metal therein and separate compartments for holding lethal vapor and bursting charge, the walls of said compartments being integral with each other.
- 20 4. A drawn gas projectile having at its nose an indentation with relatively thin walls to provide a container or chamber for a bursting charge and having at its opposite end a closed-in portion, the walls of which are thicker than the walls of the body portion of the projectile.
- 25 5. A drawn gas projectile having integral base, body and nose portions, the nose having an indentation holding a bursting charge and the wall of said projectile being progressively thinner from the base to the nose.
- 30 6. In a drawn gas projectile having integral base, body and nose portions, a chamber containing lethal vapors and a separate chamber formed by an indentation in the

nose containing a bursting charge, the wall 40 of said projectile being of greatest thickness at the base and of least thickness at the nose.

7. In a drawn gas projectile having integral base, body and nose portions, a chamber containing lethal vapors and a separate chamber formed by an indentation in the nose containing a bursting charge, the wall 45 of said projectile being progressively thinner from the base to the nose.

8. A process of making a drawn gas projectile, consisting of first cupping a circular metallic plate, then forming a thimble from the cupped plate, then indenting the closed end of the thimble to provide a container 55 or chamber for a bursting charge which has relatively thin walls, and then closing in the opposite end of the thimble to form a base portion with relatively thick walls as compared with the walls of the body and 60 the indented end of the thimble.

9. A process for the manufacture of a drawn gas projectile from a single circular metallic plate which consists in bending the plate to form a thimble, then indenting the 65 closed end of the thimble to form a container or cup with relatively thin walls to contain a bursting charge, and then closing in the open end of the thimble to form a base with relatively thick walls as compared with the indented end and the body portion of the projectile.

In testimony that we claim the foregoing as our invention we have sign'd our names this 12th day of June, 1919.

FREDERICK HOWARD LIVENS.
